INVENTOR
C. T. SMALL
BY ATTORNEY

UNITED STATES PATENT OFFICE.

CHESLEY T. SMALL, OF ST. LOUIS, MISSOURI.

CAP-FEEDING MACHINE.

Application filed February 14, 1921. Serial No. 444,640.

To all whom it may concern:

Be it known that I, CHESLEY T. SMALL, a citizen of the United States of America, residing at the city of St. Louis, State of Missouri, United States of America, have invented a certain new and useful Cap-Feeding Machine, of which the following is such a full, clear, and exact description as will enable any one skilled in the art to which it appertains to make and use the same, reference being had to the accompanying drawings, forming part of this specification.

My invention relates to a cap feeding machine and more particularly to improvements in that form of cap feeding machine shown and described in application Serial No. 413, 189 filed by me September 27, 1920.

The object of my invention is to provide improved means for controlling the flow of caps to the rotary disc or feed table of the machine, so as to prevent clogging of the caps such as may under certain conditions occur in the type of machines referred to.

In the accompanying drawings which illustrate one form of device made in accordance with my invention, Figure 1 is a vertical central section and Figure 2 is a top plan view.

5 indicates a rotary disc or feed table carried on a vertical shaft 6. Arranged above the feed table 5 is an annular wall 7, the interior of which is divided into two parts by a partition 8, one of said parts being provided with an inclined cover 9. 10 is a peripheral outlet through which the caps are forced by a centrifugal action into a chute 11. 12 are legs for supporting the machine. All of the above parts are similar to those shown and described in my prior application above referred to.

The caps flow from a hopper, or other suitable source of supply, through a vertical chute 15 terminating in an inclined portion 16 preferably arranged at an angle of about 45° and supported by brackets 17. The discharge end of the inclined portion 16 is provided with a vertical door 18 pivoted at 19. Carried by the door 18 is an arm 20 on which is slidably mounted a weight or counterpoise 21 adapted to be secured in position by means of a set screw 22. 23 is a

cable or cord attached at one end to the arm 20 and passing around a pulley 24 mounted in a supporting arm 25 carried by the inclined portion 16 of the feed chute. The other end of the cord 23 is carried to any suitable point within the reach of the operator of the machine to which the caps are to be delivered.

Owing to the inclined position of the part 16 of the feed chute and the vertical position of the door 18 the caps are supplied to the feed disc 5 in such a manner as to prevent clogging. At the same time the number of caps which are fed through the chute 65 can be readily regulated by the operator of the machine through the medium of the cord 23 controlling the counterpoised door 18.

Having fully described my invention what I claim as new and desire to secure by Letters Patent of the United States is:

1. In a device of the class described, the combination with a horizontal support for the caps, said support being provided with a peripheral outlet and a passage restricted in height leading thereto, of a feed chute for delivering caps to said support, said feed chute at the point of discharge on said support being inclined toward said restricted passage.

2. In a device of the class described, the combination with a rotary horizontal support for the caps, said support being provided with a peripheral outlet, of a feed chute for delivering caps to said support, 85 said feed chute being inclined at the point of discharge upon said support and means for controlling the flow of caps through said chute.

3. In a device of the class described, the combination with a rotary horizontal support for the caps, said support being provided with a peripheral outlet, a segmental cover for a portion of said support adjacent to said outlet and open along its inner 95 periphery for the passage of single caps, of a feed chute for delivering the caps to said support, said feed chute being inclined at the point of discharge upon said support and means for controlling the flow of caps 100 through said chute.

4. In a device of the class described, the

combination with a rotary horizontal support for the caps, said support having a peripheral outlet, a segmental cover for a portion of said support adjacent to said outlet and open along its inner periphery for the passage of single caps, of a feed chute for delivering caps to said support, said feed chute

being inclined toward the inner periphery of said cover at the point of discharge upon said support, and a door for controlling the flow of caps through said chute.

In testimony whereof, I have hereunto set my hand and affixed my seal.

CHESLEY T. SMALL. [L.S.]
